CONFECTION

Isadore Herman, 1040 5th Ave., New Kensington, Pa.

Filed Feb. 5, 1962, Ser. No. 68,650

Term of patent 14 years

(Cl. D82—2)

FIG. 1

FIG. 2

FIG. 3

FIG. 4

The essential features of the design are shown in full lines on the drawing.

I claim:

The ornamental design for a confection, as shown and described.
